PERFORATING MACHINE

Rudolph Becker, North Plainfield, N. J., assignor
to The Singer Manufacturing Company, Eliza-
beth, N. J., a corporation of New Jersey

Application August 11, 1936, Serial No. 95,323

5 Claims. (CL. 164—87)

This invention relates to machines for feeding and perforating material and has for an object to provide a machine which will rapidly make rows of clean-cut perforations in the work and which may be readily adjusted and maintained in efficient operative condition.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 of the drawings is a rear side elevation of a perforating machine embodying the invention. Fig. 2 is a section on the line 2—2, Fig. 1, reversed end for end. Fig. 3 is a front end elevation of the machine. Fig. 4 is an enlarged vertical sectional view through the reciprocatory anvil-carrying bar of the perforating mechanism. Figs. 5 and 6 are, respectively, sections on the lines 5—5 and 6—6, Fig. 2. Fig. 7 is an enlarged vertical section through the coating elements of the perforating mechanism taken in the line of feed of the machine. Fig. 8 is a similar view taken transversely of the line of feed. Fig. 9 is a fragmentary view of the machine showing a felt hat in position to receive one or more rows of perforations circumferentially of its crown. Fig. 10 is a face view of a work-guide used with the machine, and Fig. 11 is a perspective view of the work-support block and punch element carried thereby.

In the main, the present machine is preferably constructed along the lines of a cylinder-bed sewing machine and, like a sewing machine, has a frame including a standard 1 carrying a cylinder bed or work-supporting arm 2 and an overhanging bracket arm 3 terminating in a head 4.

There is mounted in the head 4, in lieu of the usual sewing machine needle-bar, a reciprocatory anvil-bar *a* comprising two sections 5 and 6, Fig. 4, the former of which is tubular and at its lower end telescopically receives the shorter solid section 6 which at its lower end is socketed to receive the anvil member 7 preferably made of brass and secured in the socket in the anvil-bar by the screw 8. The portion of the solid section 6 of the anvil bar which is received in the tubular section 5 is formed with a vertical slot 9 through which passes a pin 10 fixed diametrically of the tubular section 5. This pin and slot connection prevents separation of the sections 5 and 6 of

the anvil-bar and permits a relative vertical endwise movement of such sections. A stiff coil-spring 11 housed within the tubular section 5 presses downwardly upon the upper end of the solid section 6 of the anvil-bar. The tubular section 5 is formed at its upper end with an oil hole 12.

The anvil-bar *a* is mounted to reciprocate in the bearings 13, 13 in the head 4 and the tubular section 5 of such anvil-bar is connected by the link 14 to the front end of a lever 15 which is fulcrumed within the bracket-arm 3 at 16 and at its rearward end is connected to the upper end of a pitman 17 which at its lower end embraces the ball-crank 18 on the main shaft 19 carrying the balance-wheel and power-receiving belt-pulley 20 common to sewing machines.

Mounted within the cylinder-bed 2, below the work-plate 21 thereof, is the tubular punch-element 22 having at its upper end a sharpened circular edge 23 which cuts against the flat lower end 24 of the anvil 7. The passageway 25 within the punch 22 has a lateral discharge opening 26 for the chips or punchings 27, Fig. 8. The reduced cylindrical lower end-portion 28 of the punch 22 is received in a socket 29 in the work-support block 30 which is secured by the screw 31 in the slideway 32 extending horizontally across the free end of the frame of the work-supporting arm 2. The clearance hole 33 in the block 30 for the shank of the screw 31 is large enough to permit a limited adjustment of the block 30 in the slideway 32. The punch 22 is held in its socket in the block 30 by means of the head of the screw 34. The lower end of the punch 22 is engaged by a plate 35 supported by the screw 36, Fig. 8, by turning which the punch 22 may be adjusted vertically. The punch 22 is preferably so set that it arrests the down movement of the anvil 7 slightly before the upper tubular section 5 of the anvil-bar *a* reaches its lower limit of movement; the spring 11 yielding so that a rigid or harsh engagement of the punch and anvil elements is avoided and the reaction upon the anvil-driving mechanism is cushioned.

The spring 11 is strong enough and under sufficient compression to accomplish the cutting of the material without yielding until the anvil and punch come into contact. The work-support 30 is formed at its upper end with a work-supporting surface 37 flush with the surface of the work-support 21. In the surface 37 is a depression 38 which exposes the sharpened upper end of the punch 22 also set flush with the work-supporting surfaces of the parts 21 and 30. The depression 35

38 receives the portion of the work immediately surrounding the hole being cut, when the work is depressed by the anvil member 7, as shown in Figs. 7 and 8.

For feeding the work step-by-step, in timed relation with the reciprocatory motion of the anvil-bar *a*, the machine may be provided with a four-motion feed-dog 39 such as is common to sewing machines. The feed-dog 39 is preferably of inverted L-shape in top plan, as shown in Fig. 2, i. e., it has a notch or cut-out 39' in which the punch 23 is located and has work-engaging teeth in rear of the punch 23 and other teeth at one side of the punch 23. The feed-dog 39, by engaging the work at the side of as well as in rear of the punch 23, is thus well adapted to lift or strip the work from the punch-element 22 in its rising movement. The feed-dog 39 is rigidly mounted on one end of the feed-bar 40 which extends lengthwise of the cylinder bed 2 and, at its opposite end has fixed thereto a casting 41 which is journaled on the horizontal cross-pin 42 fixed to the side lug 43 on the vertical sleeve 44 which latter is journaled on the fixed vertical stud-pin 45 mounted in the machine frame. The feed-bar 40 is thus mounted for universal movement at its end remote from the feed-dog 39.

Projecting forward horizontally from the feed-bar is a pin 46 which enters a hole 47, Fig. 5, in an eccentric follower 48 embracing the feed-lift eccentric 49 on the main shaft 19. This eccentric moves the feed-dog 39 up and down or into and out of engagement with the work.

Projecting vertically from a bracket 50 fixed to the feed-bar 40 is a pin 51 which enters a hole in the eccentric follower 52 embracing the conventional adjustable feed-advance eccentric 53 on the main shaft. The eccentric 53 imparts the feed-and-return components of motion to the feed-dog 39.

Opposed to the feed-dog 39 is the presser-foot 54 having a clearance aperture 55 for the anvil element 7. The presser-foot 54 is mounted on the presser-bar 56 which slides vertically in bearings in the head 14 and is pressed downwardly by the spring 57 the pressure of which may be regulated by the screw 58. The presser-foot and bar may be raised for insertion and removal of work by manipulation of the usual treadle-controlled presser-lifting lever 59, fulcrumed at 60 on the bracket-arm 3 and extending under the roller 61 journaled on the screw 62 mounted on the presser-bar 56. It may also be raised by manipulation of the usual hand-operated cam-lever 63 fulcrumed at 64 on the head 4 and having its cam-portion 65 arranged to engage under and lift the extreme forward end of the lever 59 immediately below the roller stud 62.

The machine may be equipped with suitable guides to assist in directing the work to the perforating mechanism. In perforating the crowns of felt hats, for example, it is desirable to provide a throw-out guide 66 for engaging the brim 67 of the hat at its juncture 68 with the crown 69, to evenly space the initial row 70 of perforations from the base of the crown. The guide 66 is secured by the screw and slot expedient 66', Fig. 10, for vertical adjustment on the carrier 71 which is frictionally pivoted at 72 on the slotted arm 73 adjustable horizontally on the bracket 74 secured to the head 4 by screws 75. The slot in the arm 73 is entered by the steady pin 76 and fastening screw 77. When not in use, the guide 66 may be shifted or swung to an out-of-the-way position, as shown in Fig. 1.

To space the row of perforations being made from a preceding row, an indicating guide 78 may be used. This guide is in the form of a blunt pointed down-turned finger which terminates alongside the presser-foot 54 and has its horizontal shank 79 secured in a block 80 mounted on the presser-bar 56 and adjustable vertically thereon; the shank 79 being horizontally and rotatively adjustable in the block 80.

The feed-dog 39, in its rising movement, lifts the work clear of the punch 22 and feeds it one step, whereupon the feed-dog drops below the work-support and the anvil descends to effect the cutting of a new hole; the feed-dog returning below the work to position for another rising and feeding movement.

The chips or punchings 21 discharged from the punch 22 fall within the end cap 81 into the chute 82 which leads downwardly and toward the standard 1 where the chips may be discharged into a suitable receptacle, not shown.

The punch 22 is readily removed for sharpening its cutting edge 23 by loosening the holding screw 34 and sliding the punch upwardly out of the socket 29 in its carrier block 30. The anvil 7 is easily removed for dressing its lower flat end face 24 by loosening the screw 8 and sliding the anvil downwardly out of its socket in the lower section 6 of the anvil-bar.

The foregoing description of a preferred embodiment of the invention is to be read in a purely illustrative sense and not in limitation of the invention. The details of construction and relative arrangements of parts may obviously be variously modified by those skilled in the art within the spirit and scope of the invention as defined in the appended claims.

Having thus set forth the nature of the invention, what I claim herein is:—

1. In a perforating machine, a work-support, a presser-foot above the work-support, a four-motion feed-dog below the work-support, a punch below the work-support, and a reciprocatory anvil mounted above the work-support and working in timed relation with said feed-dog.

2. In a perforating machine, a work-support having a depression therein, a presser-foot above the work-support, a four-motion feed-dog below the work-support, a stationary punch projecting upwardly from the bottom of the depression in said work-support, and a reciprocatory anvil mounted above the work-support in position to engage said punch.

3. A perforating machine having a work-supporting block formed in its work-supporting face with a depression, a punch-element rising from the bottom of and within said depression, a feed-dog having work-engaging teeth arranged to strip the work from the punch-element preparatory to feeding the work, and a reciprocatory anvil-element opposed to said punch-element.

4. A perforating machine having a frame including a bed and an overhanging bracket-arm, a reciprocatory anvil-bar comprising telescopically arranged sections, a spring interposed between said sections and housed within said bar, an anvil carried by said anvil-bar, a punch-element stationarily mounted in said bed, and a four-motion feed-dog arranged to work closely adjacent said punch-element.

5. The combination with a notched feed-dog and a presser-foot, of a stationary punch-element located in the notch in the feed-dog, and a reciprocatory anvil element cooperating with the punch-element.
